UNITED STATES PATENT OFFICE.

JOSEPH STANLEY, OF HUNTINGTON, INDIANA.

AUTOMATIC SIGNALING APPARATUS FOR LOCOMOTIVES.

1,108,015.

Specification of Letters Patent. Patented Aug. 18, 1914.

Application filed December 6, 1913. Serial No. 805,067.

To all whom it may concern:

Be it known that I, JOSEPH STANLEY, a citizen of the United States, residing at Huntington, in the county of Huntington and State of Indiana, have invented certain new and useful Improvements in Automatic Signaling Apparatus for Locomotives; and I do hereby declare the following to be a full, clear, and exact description of the invention, such as will enable others skilled in the art to which it appertains to make and use the same.

The present invention relates to signaling apparatus for railway locomotives, and has for its purpose to provide a device which is automatically operable to effect the sounding of the signal at predetermined points along the roadway whereby to absolutely insure the sounding of the warning at such places, without requiring any attention on the part of the engineer, thus leaving him free to his other duties.

A further purpose of the invention is to provide an apparatus which may be used in connection with the usual locomotive steam whistle, to the end of equipping any locomotive with the device without requiring any alteration in its construction; and wherein the construction of the apparatus is simple and may be produced at small cost.

With these and other objects in view the invention consists in the novel details of construction and combinations of parts more fully hereinafter disclosed and particularly pointed out in the claims.

In the accompanying drawings forming a part of this application, and in which similar reference symbols indicate corresponding parts in the several views: Figure 1 illustrates the application of the invention to a locomotive. Fig. 2 is a detail and side elevational view of the track engaging member and its associated parts. Fig. 3 is a front elevation of the same, with parts removed to show the inner construction. Fig. 4 is an enlarged detail view of the valve rod. Fig. 5 is a transverse sectional view taken on the line 5—5 of Fig. 2. Fig. 6 is a transverse sectional view taken on the line 6—6 of Fig. 4; and Fig. 7 is a detail view, partly in elevation and section, of the steam chest and controlling slide valve.

Referring to the construction in further

detail, A designates an ordinary locomotive having the usual steam dome B, and on which is mounted the whistle 1. A casing or frame 2 is mounted on the cab C of the locomotive and contains a mechanism for automatically effecting the blowing of the whistle 1 at predetermined points along the roadway. The whistle 1 is adapted to be sounded by steam taken from the boiler dome B, through a pipe 3 leading to a steam chest 4, and from which the steam is communicated directly to the whistle through the pipes 5 and 6. The pipe 5 is connected to communicate with the steam chest 4 at opposite ends by sections 7 and 8, as in the manner clearly shown in Figs. 1 and 7, 70 and the purpose of which will be presently explained. The usual throttle lever 9 is fulcrumed in the cab at 10, and is connected to actuate the slide valve 11 mounted in the steam chest 4 and adapted to control the 75 passage of steam from the chest through either of the pipes 7 and 8, or to shut off such flow as desired. Said connecting means consists of a rod 12 connecting the lever 9 with a lever 13 fulcrumed at 14, 80 and said lever 13 is in turn connected to the valve stem 15 by a link 16, (see Fig. 7). The slide valve 11 is kept within its true path of movement by a pair of grooved members or strips 17 secured to the bottom 85 of the steam chest and providing guideways. From the foregoing it will be clearly seen that when said throttle lever 9 is moved to its forward or reversed position, communication is established between the steam 90 chest 4 and the steam pipe 5 through either of the pipe branches 7 or 8, and further, that when said throttle lever 9 is in an intermediate position (as shown in Fig. 1), the slide valve 11 will close communication 95 between the steam chest and both of said pipes (as shown in Fig. 7).

The valve 11 is connected to the valve rod 15 through the medium of a pair of lugs 11^a through which said rod passes, and between said lugs a nut or pin 12^a is secured to the rod and forms an abutment for the pair of oppositely acting springs 13^a whose distal ends are disposed against the lugs 11^a. By this form of connection between 100 the valve and its actuating rod said valve has a resilient sliding movement which avoids any liability of binding, and it is

self-centered or seated to close the pipes 7 and 8 when the lever 9 is moved to its intermediate position.

In the ordinary running of the locomotive 5 communication between the steam pipes 5 and 6 is shut off or interrupted by the mechanism contained within the housing or frame 2, and communication is established between the pipes 5 and 6 to effect the sounding 10 of the whistle through the operation of this apparatus, which is performed automatically.

The casing consists of two similar sections 19 and 20 provided with two pairs of guides 15 21 and 22, between which are mounted a pair of grooved blocks 23 carrying a shaft 24 on which is journaled a wheel 25. A second pair of blocks 26 are mounted on the side members beneath the blocks 23 and 20 provide supporting members for the latter. A cross-head 27 is mounted on the blocks 23 and carries a valve rod 28. The open spaces between the sections 19 and 20 and the valve rod 28 are closed by the sectional 25 block 29, secured in any suitable manner.

The pipes 5 and 6 enter the space provided for the working of the rod 28, and have their adjacent and open ends disposed in aligned and close proximity. The rod 28 30 has a squared section 30 which works within a suitable chamber formed in the sectional block 29, and said squared section is formed with an elongated opening or aperture 31, adapted to register with the openings 35 through the pipes 5 and 6 and provide communication therebetween when said rod is moved upwardly, and the valve 32 is mounted in said squared section 30 of the rod and is adapted to seat against and close the end 40 of the pipe 5 when the rod is at its lowermost position, *i. e.*, its normal position. Said valve 32 is mounted within a recess 33 formed in the face of the section 30, and is itself recessed to receive a pressure spring 45 34 (see Fig. 6). A pair of springs 35 are disposed between the side block sections 29 and the cross-head 27, and to either side of the rod 28, and have for their purpose to act against said cross-head and hold the 50 same under tension at its lowermost position, *i. e.*, with the valve 32 closed against the open end of the pipe 5. The wheel 25 is adapted to be raised to move the rod 28 and uncover pipe 5, whereby to effect the 55 sounding of the whistle, through the medium of raised track sections 36 that are disposed to either side of the main rails 37 and at the proper intervals along the roadway. Thus it is proposed to place these 60 raised track sections to either side of grade crossings, to the end that the whistle will be blown automatically before reaching such crossings without requiring this to be done on the part of the engineer.

65 It is obvious that those skilled in the art

may vary the details of construction and arrangement of parts without departing from the spirit of my invention, and therefore I do not wish to be limited to such features except as may be required by the 70 claims.

I claim:

1. The combination with a railway locomotive having a steam whistle, of means for automatically sounding the whistle comprising a steam pipe connected to the whistle; a supporting frame mounted on the locomotive; blocks slidably mounted in said frame; a rod mounted on said blocks and having an opening adapted to register with said steam pipe and form a through 75 passage therewith; springs engaging with said frame and normally holding the rod in position to obstruct said passage; a wheel carried by said blocks; and a raised track section adapted to engage with said wheel to move the rod and bring said rod opening into register with the steam pipe whereby to sound the whistle, substantially as described.

2. The combination with a railway locomotive having a steam whistle, of means for automatically sounding the whistle comprising a steam pipe connected to the whistle; a supporting frame mounted on the locomotive and constructed with guideways; blocks slidably mounted in said guideways; a cross-head mounted to be lifted by said blocks; a rod carried by said cross-head and having an opening adapted 90 to register with said steam pipe and forming a through passage therewith when the rod is raised; a valve carried by said rod adapted to close the passage through said pipe when the rod is in normal position; resilient means engaging with said cross-head for holding the valve rod in normal position; a wheel carried by said blocks; and a raised track section adapted to engage with said wheel to move the rod and bring said rod opening into register with the steam pipe whereby to sound the whistle, substantially as described.

3. The combination with a railway locomotive having a steam whistle, of means for automatically sounding the whistle comprising steam pipes connected to the whistle; a supporting frame mounted on the locomotive and constructed with guideways; blocks slidably mounted in said guideways; a cross-head mounted on said slidably blocks; a rod carried by said cross-head; a sectional block mounted in the frame and having a chamber through which said rod passes, said steam pipes communicating with said chambers; a valve carried by said rod adapted to obstruct the steam pipe passage into said chamber when the rod is in normal position, said rod having an opening therethrough adapted to provide communication between the pipes 115 120 125 130

when the rod is in raised position; springs seating against said sectional block and the cross-head and normally holding said valve in position to close the steam passage; a wheel carried by said blocks; and a raised track section adapted to engage with said wheel to move the rod and bring said rod opening into register with the steam pipes

whereby to sound the whistle, substantially as described.

In testimony whereof, I affix my signature, in presence of two witnesses.

JOSEPH STANLEY.
